Patented Feb. 4, 1919.

INVENTOR
Matilda Nagle

By Carl P. Giebel

ATTORNEY

UNITED STATES PATENT OFFICE.

MATILDA NAGLE, OF BROOKLYN, NEW YORK.

DYEING-MACHINE.

1,293,514.

Specification of Letters Patent.

Patented Feb. 4, 1919.

Application filed August 17, 1916. Serial No. 115,381.

To all whom it may concern:

Be it known that I, MATILDA NAGLE, a citizen of the United States, and resident of Brooklyn, in the county of Kings and State of New York, have invented certain new and useful Improvements in Dyeing-Machines, of which the following is a specification.

The present invention relates to improvements in dyeing machines, and particularly such machines for dyeing skeins of yarn or the like. An object of the invention is to provide such machines in which the skeins will be automatically turned step by step and given a swinging motion so that the dye will thoroughly permeate the skeins and the dyeing will be carried out in a uniform and superior manner. Another object is to provide in such machines means for separating the different skeins, and for permitting the convenient removal thereof.

With these and other objects in view my invention is shown in the accompanying drawings, and will be hereinafter more fully described with reference thereto and finally pointed out in the claims.

In the accompanying drawings,

Figure 1 is a side elevation of my improved machine,

Fig. 2 is a top view thereof, with parts broken away,

Fig. 3 is a vertical transverse sectional view, and

Figs. 4 and 5 are a detail section and elevation respectively of the skeins and supporting means therefor.

Similar reference characters indicate corresponding parts throughout the several figures of the drawings.

Referring to the drawings, my invention comprises a dye vat 10, provided at the upper edges of the sides with bearing supports, 11 and 12, in which the ends of shafts 13 and 14 are mounted, the said bearing supports being open at the top to permit the ready removal of the shafts. Pinions 15 and 16 are provided respectively at the end of each shaft, and mesh with gears 17 and 18 mounted upon suitable bearing supports, 19, secured to the sides of the vat. Four projecting pins, 20, are provided on the outer side of the said gears, the ratio of the said gears and pinions being four to one, that is, the movement of the gears over a distance corresponding to the distance between the pins, turns the pinion and shaft through one complete revolution.

An endless belt, 21, is mounted upon two pulley wheels, 22 and 23, rotatably supported upon brackets, 24 and 25, secured at each end of the vat, and a projection 26 provided on the belt engages the pins, 20, during the movement of the belt and thereby turns the gears step by step. It will be understood, that if desired to turn the gears at closer intervals, without increasing the speed of the belt, additional projections may be provided on the belt, or the number of pins upon the gears increased and the ratio correspondingly changed. This belt is driven by another belt 27, extending over a pulley 28 provided on the shaft of the pulley 23, or any other suitable means may be employed for driving the belt.

Elongated eccentrically mounted plates, 30 and 31, are provided in pairs upon the shafts, in spaced relation, and between which the skeins of yarn are placed. A web or feather piece 32 is disposed between the plates 30 and 31 extending downward from the shaft and serves to give to the yarn a circular swinging motion. The webs are of sufficient length so that the yarn during its intermittent turning will not slip and the circular path of the web is of such diameter as to give the yarn a considerable swinging movement, this movement being similar, and in fact superior, because of its uniformity, to the approved methods of poling the yarn by hand.

It will be understood that additional skein supporting shafts may be provided if desired, and partitions may be placed in the vat so that two or more different colored dyes may be placed therein.

I have illustrated and described a preferred and satisfactory form of my invention but it is obvious that changes may be made therein within the spirit and scope thereof or defined in the appended claims.

I claim,

1. In a dyeing machine, the combination with a vat, of a yarn supporting shaft, yarn retaining plates disposed in spaced relation on said shaft, and an elongated web between said plates, the axis of said shaft being within the cross section of said web, and relatively closer to one longitudinal edge than the other, said web adapted to impart swinging and displacing movement to said yarn, and means for imparting rotary motion to said shaft.

2. In a dyeing machine, the combination

110

with a vat of a yarn supporting shaft, rotatably mounted upon said vat, a pinion on said shaft at one end thereof, a gear meshing with said pinion, pins provided in spaced relation on said gear, and an endless belt provided with a projecting member adapted to engage said pins to turn said gear, to intermittently rotate said shaft.

Copies of this patent may be obtained for five cents each, by addressing the "Commissioner of Patents, Washington, D. C."

In testimony, that I claim the foregoing as my invention, I have signed my name in presence of two subscribing witnesses.

MATILDA NAGLE.
